ELECTRICAL CUTOUT

Carl E. Mosley, Overland, Mo., assignor to W. U. Matthews Corporation, St. Louis, Mo., a corporation of Missouri

Application June 26, 1944, Serial No. 542,106

11 Claims. (CL 200—116)

1 This invention relates to electrical cutouts, and with regard to certain more specific features, to fuseless cutouts.

Among the several objects of the invention may be noted the provision of a resettable thermally-operated cutout employing improved arc-extinguishing features; and the provision of apparatus of this class which is simple, reliable and economical to build. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which are illustrated several of various possible embodiments of the invention,

Fig. 1 is a vertical section showing one form of the invention in closed-circuit position;

Fig. 2 is a horizontal section taken on line 2—2 of Fig. 1;

Fig. 3 is a fragmentary view similar to the upper portion of Fig. 1 but showing an initial releasing and shunting action;

Fig. 4 is a view similar to Fig. 1 but on a reduced scale and showing a final arc-extinguishing action;

Fig. 5 is a right-hand elevation of Fig. 1 on a reduced scale, parts being broken away to show certain features;

Fig. 6 is a front elevation of a multi-tube form of the invention, parts being broken away;

Fig. 7 is a right-hand elevation of Fig. 6, parts being broken away;

Fig. 8 is a horizontal section taken on line 8—8 of Fig. 6;

Fig. 9 is a vertical section taken on line 9—9 of Fig. 7; and,

Fig. 10 is a vertical section showing the apparatus in switch-open condition.

Similar reference characters indicate corresponding parts throughout the several views of the drawings.

Referring now more particularly to Fig. 1, there is shown at numeral 1 a bracket which centrally supports a peripherally grooved vertical insulator 3. The insulator has formed through it a hole 5 for the reception of an insulating and also de-ionizing tube 7. This tube has a tight enough fit in the opening sides to support itself therein, or if desired, it may be held in any other suitable manner. It is composed of a suitable de-ionizing material such as horn fibre, or the like. Besides

2 its de-ionizing characteristic, it also constitutes an insulating lining for the opening side.

Supported on the upper end of the insulator 3 is a conducting clamp portion 9 of a conducting bracket 11. The clamp is provided with a suitable wire connector 13 by means of which current is brought to the apparatus.

The bracket 11 supports an insulating platform 15. This platform 15 in turn supports a conducting block 17, screw fasteners 19 being used for the purpose. Block 17 includes an opening 21 which is co-axial with the opening through the tube 7. At the lower end of the opening 21 is a circular, conducting beveled seat 23 with which engages the upper beveled rim of a conducting contact cup 25.

The cup 25 is slidably supported upon an operating plunger rod 27. At the upper end of stem or rod 27 is a disc-like head 29 adapted under suitable circumstances to descend through the opening 21 and strike within the cup 25. The plunger 27 extends downward through the tube 7 and through a slide bearing 31 of a lower conducting bracket 33. This bracket 33 is bridge-shaped, as indicated in Figs. 1 and 5, and by means of screws 35 is attached to a conducting clamp 37 fastened around the lower end of the insulator 3. This clamp also carries a line wire connector 39 forming a second connection to the circuit in which the device is located.

The stem 27 is positively electrically connected with the bracket 33 through a long flexible pigtail wire 39. The stem is also biased downward by means of a tension coil spring 41. This spring at its lower end 43 is fastened to the bracket 33. At its upper end it is fastened to a fixed collar 45 on the stem 27. A compression spring 47 normally biases apart the conducting cup 25 and the collar 45. A conducting pigtail wire 49 places the collar 25 and stem 27 in positive conductive relationship. At the lower end of the stem 27 is an eye 51 by means of which it may be pushed up manually, as will appear.

Fastened to the support 17 by means of screws 53 is a vertical conducting bracket 55 forming an upper clevis 57 for a catch 59. Pivoting of the catch 59 is on a clevis pin 61. Its counterclockwise motion is limited by a stop 63. A spring 65 biases the catch 59 in a counterclockwise direction. A pigtail wire 67 assures good electrical conduction between the catch 59 and the support 55. A second clevis 69 supports a latch 71. This is carried on a pin 73 and is biased counterclockwise by means of a spring 75. This latch 71 includes a holding finger 77 adapted

to swing under the head 29 (compare Figs 4 and 1). The upper surface of the finger 77 is flat so that it may support the head 29 in the position of parts shown in Fig. 1. It allows upward passage of the head 29 in the position of parts shown in Fig. 4. A spaced lug 79 is engageable by the head 29 when the latter is raised. This forces the latch 71 clockwise from a position such as shown in Fig. 4 to that shown in Fig. 1. Clockwise motion of the latch 71 causes a finger 81 thereof to ride under the hook-shaped end 83 of the catch 59, there to be held as indicated in Fig. 1.

Thus the hook 83 supports the finger 81 and holds the latch 71 in its clockwise position shown in Fig. 1. In this position the finger 77 of latch 71 supports head 29 and holds the entire rod 27 against the pull of the stretched spring 41. The collar 45 is so positioned that under these conditions the contact cup 25 is pushed into good electrical contact with the beveled edge 23. The spring 41 is at this time under compression.

The latch 71 is also provided with a switch blade 85 which, when the latch rotates counter-clockwise is engageable with a stationary spring contact 87. This contact, through a conducting bolt 89 is in conductive relation with the bracket 11 and clamp 9.

At numeral 91 is shown a thermostatic element which at one end is connected to a conducting bolt 93, placing it in conductive relation with the bracket 11 and clamp 9. The other end of the thermostatic element is attached at 95 to an extending portion of the catch 59. Thermostatic elements of different ratings can be interchanged. The character of the element 91 is described in Parsons United States Patent 2,121,259, dated June 21, 1938. It consists of bimetallic material wound along a minor helix and the resulting minor-wound material is then wound along a major helix. The bimetallic member so made will expand and contract in the direction of the axis of the major helix when the temperature of the structure 91 is changed. By passing current through the helix the temperature may be changed.

The described result in the major helix is due to the fact that the winding of the minor helix is such as to produce a torsional or twisting effect along the axis of the minor helix when the temperature changes. In accordance with one or the other metal of the bimetallic members being positioned outside or inside of the minor helix, the major helix will expand or contract along its axis when heated. The rule is that the device will contract axially along the axis of the major helix in response to heating when the metal of lesser coefficient of frontal expansion is outside, and the present device is so arranged. Thus when current passes through the thermostatic element 91, the element tends to heat and to contract lengthwise. An advantage of the particular form of the thermostat is that the degree of movement produced in response to current is great while the amount of space occupied by the thermostat is small. It is to be understood that other equivalent thermostatic elements may be used for controlling the catch 59. A cover for all of the latch, catch and associated parts is shown at numeral 2.

Operation of the first form of the invention shown in Figs. 1-5 is as follows, starting with the Fig. 1 position:

Current flows through the line wire connectors 13, clamp 9, bracket 11, bolt 93, thermostatic

element 91, catch 59, pigtails 67, conducting parts 55, 17, cup 25, pigtails 49, rod 27, pigtails 39, bracket 33, clamp 31 and out to the line via the lower line wire connector 39. Under normal current conditions the heating of the thermostatic element 91 is negligible and it maintains a length such that the catch 59 maintains the latch 71 in the switch-closed position shown in Fig. 1.

Upon overload current flowing through the thermostatic element 91, it contracts and rotates the catch 59 clockwise. This releases the latch 71 as shown in Fig. 3. Thereupon the switch 85, 87 is closed while the head 29 is released. As soon as the switch 85, 87 closes, the thermostatic element 91 is shunted out of the circuit so that any further current flow under arcing conditions will not damage it. At this time the finger 77 releases head 29. The spring 41 draws down the rod 27. As collar 45 descends the cup 25 for a short interval is maintained in contact with seat 23. After a short period of time head 29 strikes its seat in cup 25 and thereafter the contact cup 25 is withdrawn from the contact 23 (see Figs. 3 and 4). Any arc that is formed in the de-ionizing tube 7 is from part 17 to cup 25 and not to head 29. This prevents damage to the head 29 by the arc while the arc is being snuffed out.

To reclose the circuit an operator pushes up the eye 51, whereupon the contacts 25 and 23 are first closed. Then, the additional lost motion available between the stem 27 and the cup 25 raises the head 29 into engagement with the lug 79, thus forcing the latch 71 clockwise into position to be caught by the catch 59. As a preliminary the switch 85, 87 also opens. If the thermostatic element 91 has at this time cooled down enough to elongate the element so that the catch 59 will hold the latch 71, the switch remains closed upon releasing ring 51. Otherwise, it will reopen.

The form of the invention shown in Figs. 1-5 is very compact, the substantially cylindric vertical and hollow insulator 3 forming the sole mount therefor. It will also be noted that the lost motion between the contact cup 25 and the rod 27 permits the rod to get into motion before the contacts 25 and 23 separate. Before separation the spring 41 maintains the contact. Then when the cap 29 strikes the interior of the cup 25, the contact is suddenly broken which is a desired optimum condition.

In Figs. 6-10 is shown another form of the invention in which multiple breaks are made in multiple tubes. In this form of the invention numeral 101 indicates the supporting bracket with which the fuseless cutout can be mounted on an insulator (insulator not shown). Bracket 101 also supports an extension 103. On the extension 103 is fastened an insulating crossbar 105 having suitable openings into which are threaded de-ionizing, insulating tubes 107. These are open at their lower ends. On these tubes are enclosing conducting caps 109, one of which is shown in detail section in Fig. 9. A description of one will describe both.

Each cap carries a wire connector 111 for one lead 113 of the circuit. Threaded into each cap 109 is a bushing 115 which forms a bearing for a sliding pin 117. The lower end 119 of pin 117 is cup-shaped and forms a contact. A compression spring 121 reacts from the upper end of the bushing 115 to the top of the contact 119, thus biasing the contact downward. A pigtails 123 assures good electrical connections between the member 115 and the parts connected with the contact 119. A

head 125 on the pin 117 limits its downward motion from the bias of spring 121.

Extending through the tubes 107 are respective rods 127, the upper ends of which are formed as contacts 129 for engagement with the resilient contacts 119. These rods 127 extend respectively from the lower open ends of the tubes 107 and are connected to an insulating crosshead 129. This crosshead has an opening 131 by means of which it slides upon a central guide bar 133, the latter extending downward from the extension 103. Rotation of the crosshead 129 on the guide 133 is prevented by the guiding action of the rods 127 operating in the tubes 107.

A bracket 135 supports an insulating extension 137 which in turn supports an insulating disc 139. The last-mentioned parts 135, 137 and 139 are held together by means of screws 141 and 143.

On the disc 139 is supported a conducting clevis 145 for a catch 147 pivoted at 149 and normally biased clockwise by means of a spring 151. Also pivoted to the clevis 145 at 153 is a latch 155 carrying a holding finger 157 and a lug 159. The latch is biased clockwise by a spring 160. A thermostatic element 161 corresponding to the element 91 of the first form of the invention, is attached to the end of the catch 147, as indicated at 163. The other end of the thermostatic element 161 is attached to the screw 141 which passes through the members 137 and 139 and into conductive threading relations to the conductor 135. The conducting part 135 is connected to one of the rods 127 by a bus bar 167 (see Figs. 6 and 8 particularly). One of the screws 169 which holds the clevis 145 is placed in conducting relation to the other rod 127 by means of a second bus bar 171 (see said Figs. 6 and 8). A pigtail wire 173 assures proper electrical conduction between the clevis 145 and the catch 147. A cover 102 is attached to the disc 139 forming a protection over the described thermostatic and latch parts.

The entire assembly of parts on the crossbar 129 may be moved up from the Fig. 10 position to the Fig. 7 position. In the Fig. 7 position stop nuts 8 on guide 133 limit downward motion of crosshead 129. In order that the said assembly may be latched up in the Fig. 7 position, an insulating extension 175 is carried on the part 103. To this extension 175 is attached a downwardly directed hook 177 engageable with the lug 159 when the latter rises with its assembly. This engagement moves the latch 155 counterclockwise until it is caught by the catch 147 as indicated in Fig. 7. Thereafter the finger 157 is held by the hook 177. In this position of parts the rods 127 are lifted and inserted into the tubes 107, thus placing the movable contacts 129 in engagement with the resilient contacts 119. Current then flows down the right-hand rod 127 (Fig. 6) across the bus bar 167 (Fig. 8), thence through the conductor 135, screw 141, thermostatic element 161, catch 147, pigtail 173, clevis 145, one of the screws 169, bus bar 171, through the other rod 127 and back to the line. These conditions prevail as long as not enough current is passing through the thermostatic element 161 substantially to contract it. Upon overload current, heating of the element 161 contracts it, thus rotating the catch 147 counterclockwise and releasing the latch 155. This permits the assembly of the crossbar 129 and parts thereon to descend from the position shown in Fig. 7 to that shown in Fig. 10, stops 8 limiting the downward motion. This breaks the circuit practically simultaneously in two places, namely, at the pairs of contact 119, 129 in the

tubes 107. To reclose the circuit, the said assembly is again raised from the position shown in Fig. 10 to that shown in Fig. 7.

The arc-extinguishing de-ionizing effect of each tube 107 is similar to that of tube 7 of the first form of the invention.

Although only two tubes 107 and two sets of associated parts are shown in Figs. 6-10, a greater plurality may be used without departing from the principles of the invention.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. In an electrical cutout, a substantially hollow cylindric insulator, a coaxial de-ionizing tube passing through said insulator, a fixed contact supported at the upper end of the insulator, a conducting rod passing through said tube, a movable contact having a lost-motion support on said rod, a compression spring reacting from a point on the rod against said movable contact normally to bias it against the fixed contact, a tension spring normally biasing said rod out of said tube, said rod extending upward past the fixed contact and being provided with means for holding it, a latch mechanism carried at the adjacent end of the insulator and engageable with said rod-holding means, and means for holding said latch mechanism in a holding position under normal circuit condition and for releasing it under overload conditions, said holding means on the rod being engageable with the latch means to set the latter into holding position and to be released thereby to permit bias of said tension spring to open the contacts.

2. In an electrical cutout, a de-ionizing tube, a fixed contact supported at the one end of the tube, a conducting rod passing through said tube, a movable contact having a lost-motion support on said rod, a compression spring reacting from a point on the rod against said movable contact and biasing it toward the fixed contact, a tension spring normally biasing said rod in a direction out of the other end of said tube, said rod extending past the fixed contact and being provided with means for holding it, a latch mechanism carried at the adjacent end of the insulator and engageable with said rod-holding means, means for holding said latch mechanism in a holding position under normal circuit condition and for releasing it under overload circuit condition.

3. In an electric cutout, a vertical substantially hollow cylindric insulator, a coaxial de-ionizing tube passing through said insulator, a fixed contact supported at the upper end of the insulator, a conducting rod passing through said tube, a movable contact having a lost-motion support on said rod, a compression spring reacting from a point on the rod against said movable contact and biasing it toward the fixed contact, a tension spring normally biasing said rod downwardly and out of said tube, said rod extending upward past the fixed contact and being provided with means for holding it, a latch mechanism carried at the upper end of the insulator and engageable with said rod-holding means, thermostatic means for holding said latch mechanism in a holding position under normal circuit condition and for re-

leasing it under overload circuit condition, said holding means on the rod being engageable with the latch means to set the latter into holding position and to be released thereby to admit bias of said tension spring to open the contacts, and spacing means between said holding means on the rod and said movable contact allowing movement toward the movable contact upon release thereby suddenly to open said contact.

4. In an electrical cutout, a vertical substantially hollow cylindric insulator, a coaxial de-ionizing tube passing through said insulator, a fixed contact supported at the upper end of the insulator, a conducting rod passing through said tube, a movable contact having a lost-motion support on said rod, a compression spring reacting from a point on the rod against said movable contact normally to bias it toward the fixed contact, a tension spring normally biasing said rod downwardly and out of said tube, said rod extending upward past the fixed contact and being provided with holding means, a latch mechanism carried at the upper end of the insulator and engageable with said holding means, thermostatic means for holding said latch mechanism in a holding position under normal circuit condition and for releasing it under overload circuit condition, said holding means on the rod being engageable with the latch means to set the latter into holding position and to be released thereby to admit bias of said tension spring to open the contacts, spacing means between said holding means on the rod and said movable contact allowing movement upon release by the holding means before the movable contact opens and thereafter suddenly to open said contact, and switch means associated with said latch adapted to close when the latch releases and to shunt the thermostatic element.

5. An electrical cutout comprising a plurality of de-ionizing tubes, resilient switch contacts associated with said tubes, contact rods extending through said tubes and adapted to make and break engagement at said resilient switch contacts, a guide, a crosshead sliding on said guide and supporting said rods, a latch mechanism supported upon said crosshead, a thermostatic member controlling the latch mechanism and being in series circuit relation with said switch contacts and rods, and stationary holding means adapted to be engaged by the latch mechanism in a position of the crosshead wherein said switch contacts are closed, said thermostatic element under overload circuit conditions releasing the latch mechanism to allow the crosshead to move said rods into positions wherein said switch contacts are opened.

6. An electrical cutout comprising a plurality of de-ionizing tubes, resilient switch contacts associated with said tubes, contact rods extending through said tubes and adapted to make and break engagement at said resilient switch contacts, a guide, a crosshead sliding on said guide and supporting said rods, a latch mechanism supported upon said crosshead, a thermostatic member controlling the latch mechanism and being in series circuit relation with said switch contacts and rods, and stationary holding means adapted to be engaged by the latch mechanism in a position of the crosshead wherein said switch contacts are closed, said thermostatic element under overload circuit conditions releasing the latch mechanism to allow the crosshead to move said rods into positions wherein said switch contacts are opened, said tubes and guides being mounted

in an upright position, whereby gravity biases said crosshead and the parts mounted thereon toward open circuit positions.

5 7. An electrical cutout comprising a support, substantially vertical insulating de-ionizing tubes mounted upon said support, contacts at the upper ends of said tubes, conducting rods vertically movable in said tubes and extending from their lower ends, a substantially vertical guide, a crosshead movable under gravity down said guide and carrying said rods, a latch mechanism supported upon said crosshead and movable to a release position under normal circuit conditions and responsive to abnormal circuit conditions to assume a holding position, and means engageable by said latch mechanism for supporting it under said normal circuit conditions.

20 8. In an electrical cutout, an uprightly disposed de-ionizing tube, a contact supported at the upper end of the tube, a conducting rod extending through the tube and out of its lower end, a contact at the upper end of said rod engageable with the first-named contact and movable with the rod to and away from said first contact, means tending to move the rod out of its tube to separate the contacts, latch means adapted to hold the rod in the tube and close said contacts and when released allowing said rod to withdraw from the tube and cause opening of the contacts, and means responsive to normal load conditions in the circuit containing said contact adapted to maintain the latch closed and adapted in response to overload current in said circuit to open said latch.

35 9. In an electrical cutout, a fixed contact, a de-ionizing tube extending from said contact, a movable contact cooperating with said fixed contact, a control stem passing through said tube with respect to which said movable contact moves, a latch mechanism adjacent said opening, said control stem having a head cooperative with the latch mechanism and adapted to be held and released thereby, means biasing the stem from the tube to move said head from the latch toward said movable contact and then into the tube, resilient means reacting from a point on the stem to said movable contact normally to bias the same against the fixed contact until engaged by said head upon release of the latter from the 50 latch mechanism, whereupon the head carries the movable contact away from the fixed contact and into said tube.

10. In an electrical cutout, a fixed contact having an opening therethrough providing a circular contact seat, a de-ionizing tube extending from said opening, a movable cup-shaped contact cooperating with said circular seat of the fixed contact, a control stem passing through said tube and contact and on which said movable contact moves, a latch mechanism adjacent said opening, said control stem having a head cooperative with the latch mechanism and adapted to be held and released thereby, means biasing the stem from the tube to move said head from the latch through said opening and toward said movable contact, and resilient means reacting from a point on the stem to said movable contact normally to bias the movable contact against the fixed contact until engaged by said head upon release of the latter from the latch mechanism, said head seating in said cup shape of the movable contact upon withdrawing the latter from the fixed contact and into the tube.

75 11. In an electrical cutout, a fixed contact having an opening therethrough providing a cir-

cular contact seat, a de-ionizing tube extending from one side of said opening, a movable cup-shaped contact cooperating with said circular seat of the fixed contact, a control stem passing through said tube and contact and on which said movable contact moves, a latch mechanism adjacent the other side of said opening, said control stem having a head cooperative with the latch mechanism and adapted to be held and released thereby, spring means biasing the stem from the 10

tube to move said head from the latch toward said movable contact, spring means reacting from a point on the stem to said movable contact normally biasing the same against the fixed contact until engaged by said head upon release of the latter from the latch mechanism, said head seating in said cup shape of the movable contact to withdraw the latter from the fixed contact and into the tube.

CARL E. MOSLEY.

Certificate of Correction

Patent No. 2,401,656.

June 4, 1946.

CARL E. MOSLEY

It is hereby certified that the name of the assignee of the above numbered patent was erroneously described and specified as "W. U. Matthews Corporation," whereas said name should have been described and specified as *W. N. Matthews Corporation*, as shown by the records of assignments in this office; and that the said Letters Patent should be read with this correction therein that the same may conform to the record of the case in the Patent Office.

Signed and sealed this 6th day of August, A. D. 1946.

[SEAL]

LESLIE FRAZER,
First Assistant Commissioner of Patents.
